Primary Examiner — Jennifer L. Watkins(74) *Attorney, Agent, or Firm* — Tarter Krinsky & Drogin LLP(57) **CLAIM**

The ornamental design for a shoe, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1.1 is a front elevational view of a shoe showing the claimed design;

FIG. 1.2 is a side elevational view thereof;

FIG. 1.3 is an opposite side elevational view thereof;

FIG. 1.4 is a back elevational view thereof; and

FIG. 1.5 is a top perspective view thereof.

The broken lines define the boundary of the claimed design and form no part thereof.

1 Claim, 5 Drawing Sheets
(5 of 5 Drawing Sheet(s) Filed in Color)
